MACHINE FOR STRINGING HANGERS
AND THE LIKE

Walter J. Vail, Chicago, Ill., assignor to Vail Manufacturing Company, Chicago, Ill., a corporation of Illinois

Application June 11, 1949, Serial No. 98,507

6 Claims. (Cl. 214—8)

1

This invention is concerned with a machine to which fabricated articles, such as wire coat hangers, may be continuously fed to be suspended from a horizontal supporting arm in evenly spaced apart relation preparatory to their undisturbed transfer to a rack bar whereon the hangers are removed to a station where painting or enameling, as by spraying or dipping, is performed. Such a machine, when used in conjunction with an automatic fabricating mechanism from which the articles are fed as made, will obviate the uncertain and slow manual separation and spacing of the articles upon the rack bar which eventually receives them—an operation that is a prerequisite to the successful application of a coating such as paint or the like. In the ensuing description the term "hanger" will be used generically to designate any article whose form, size and other characteristics adapts it to be handled and strung in spaced relation upon a horizontal arm by a machine embodying the improved features of this invention.

The machine herein to be disclosed is fully automatic in that it receives the formed hangers, spaces them evenly apart upon an arm from which they are readily transferable to a removable rack bar, halts the continued feeding of hangers from the machine which continues to make and accumulate them for a brief period during which an empty supporting arm is automatically moved into receiving position, and performs these various operations automatically in timed relation so that the stringing of the hangers in spaced relation upon each supporting arm in succession proceeds as fast as the hangers are transferred from the forming machine whose output is thereby permitted to continue at full capacity. The only manual operation required is the transfer of the strung hangers off of the machine and removal thereof to the finishing station (which may be located but a few feet distant) when and as a supply of hangers are fed onto each supporting arm in evenly spaced relation; these manual operations are so easy and simple, however, that a single attendant can handle without effort the output of the present machine—something that would otherwise be impossible were the attendant also required to space the hangers apart upon the supporting rack bars which eventually receive them.

These and other objects and advantages are realized by a stringing machine embodying this invention of which a suggestive embodiment is illustrated in the accompanying drawings in the manner following:

2

Figure 1 is a side elevation of the machine; Fig. 2 is a plan view thereof; Fig. 3 is a detail in section, taken on line 3—3 of Fig. 2; 5 Fig. 4 is a vertical section, taken on line 4—4 of Fig. 1; Fig. 5 is a detail in section, taken on line 5—5 of Fig. 1; Fig. 6 is a schematic diagram of the electrical 10 control system employed; Fig. 7 is a detail in section, taken on line 7—7 of Fig. 1; Fig. 8 is a vertical section, taken on the angled line 8—8 of Fig. 2; and 15 Fig. 9 is a detail in section, taken on line 9—9 of Fig. 1.

In the present machine there is comprised a base 10 from which rises a plurality of posts 11 to support a platform 12. The space between 20 the base and platform accommodates most of the working parts and may, if desired, be enclosed for purposes of protection.

Mounted upon the base is an upstanding bracket 15 carrying a bearing 16 wherein is journaled a horizontal shaft 17 at one end of which is a pulley 18 driven from a belt 19 (see Figs. 1 and 4). This belt in turn is driven from a pulley 21 at the power delivery end of a gear reducer contained in a case 22 to which power is transmitted from a motor 23. There is affixed to the shaft 17 a beveled gear 25 in mesh with a second beveled gear 26 at the lower end of a vertical shaft 27 that is journaled for rotation in bearings 28 suitably supported as by a bracket 29 which upstands from the base 10. The upper end of the shaft 27 connects with a slip clutch 30 whose driven member 31 is notched for engagement by a stop, here shown as a lever 32 adapted to be rocked by a solenoid 33 to the operative position shown by full lines in Fig. 5; when released to the dotted line position, the lever will free the clutch for transmission of power to a driven shaft 35 which is journaled for rotation within a bearing 36 that is carried by the platform 12 (see Fig. 8). At its upper end this driven shaft 45 mounts a beveled gear 37 in mesh with a companion gear 38 that is affixed to the inner end of a horizontal shaft 40 which is rotatably supported at one end in bearings 41 contained within a tubular housing 42. A supporting structure 43 which rises from the platform 12 carries a head plate 44 whereon is rested the base of a gear box 45 providing an enclosure for the gears 37 and 38; the gear box in turn supports the housing 42 whereby the horizontal shaft 40 is ade-

quately sustained. Carried by this shaft is a plurality of helical flights 46 extending continuously for nearly the full length of the shaft to constitute therewith a feed screw which operates in the special manner hereinafter explained in detail.

An internal ring gear 47 is mounted to rotate in a horizontal plane just above the platform 12. As shown best in Fig. 8, this gear supports upon its upper face an annular turntable 48 to which it is connected as by bolts 49 which connect also with a ring 50 which is accommodated within a peripheral recess on the under face of the ring gear. The ring 50 and gear 47 cooperate to provide between them an inner raceway complementing an outer raceway 51 which, as shown, is secured in place with the aid of a positioning ring 52 that may be welded fixedly to the platform 12. A plurality of balls 53 are confined between the inner and outer raceways to provide an antifriction mounting for the internal ring gear 47 and turntable carried thereby. The position of the ring gear and turntable is such as to enclose the shaft 35 and the associated supporting structure 43 at the point where it upstands from the platform 12.

The ring gear 47 is driven by a pinion 55 in mesh with its internal teeth, the pinion being affixed to the upper end of a vertical shaft 56 which is journaled for rotation in bearings 57 that are supported within a tubular housing 58 which extends through the platform 12 and downwardly therefrom to connect with the driven element of a slip clutch 60 whose driving element is carried by a shaft 61 upstanding from a gear box 62. A coupling 64 (see Fig. 4) connects the shaft 17 with a horizontal shaft 65 extending into the gear box 62 to transmit power to the vertical shaft 56 for rotation of the turntable 48.

Extending outwardly from the annular turntable are four arms 67 spaced apart 90° (see Fig. 2), each desirably in the form of an upwardly facing channel which at its inner end terminates in a widened shoulder 68 for anchorage on the turntable as by bolts 69. These several arms are disposed tangentially of a circle that is described about the center of the turntable, such a circle having a radius equal to the distance between the turntable center and the axis of the vertical shaft 35, the purpose being to position each arm successively in alignment with the screw shaft 40.

To assure such alignment, four hardened inserts 72 are fixed in sockets that are provided in the bottom face of the annular turntable and spaced 90° apart (see Figs. 2 and 7); each insert is notched on its bottom face to provide a shoulder coacting with the top beveled end 73 of a locking bolt 74 that is mounted for vertical sliding movement through the platform to engage the shoulder of each insert 72 as it arrives in the position requisite for this purpose; the bolt at its bottom end is supported by a link connection at 75 (see Fig. 1) to one end of a rocker arm 76 fulcrumed at 77 and biased by a spring 78 to maintain the bolt in an up position with its top end 73 adjacent the annular turntable in position to engage the insert 72 next arriving opposite thereto; and a solenoid 80 having its armature in link connection at 81 with the opposite end of the rocker arm 76 so that, when energized, the solenoid armature will tilt the rocker arm to lower the bolt and free the turntable for further rotation through another 90°. The continuously rotating slip clutch 60 will advance the

turntable each time the bolt 74 is retracted, so that starting and stopping of the turntable proceeds automatically and in accordance with timing that is determined by operation of the solenoid 80.

Carried by the shaft 17 is a gear 84 (see Fig. 4) in mesh with a gear 85 that is affixed to a shaft 86 which, through a speed reducing unit 87 (see Fig. 9) drives at slow speed a shaft 88 whereon is a disc 89 mounting on one side a dog 91 and on the other side an arcuate cam 92 which extends through more than 180°. Opposite the arcuate cam is a roller 93 on one arm of a bell-crank which is pivoted at 94; the other bell-crank arm 95 is disposed adjacent the operating button 96 of a microswitch 97, the arrangement being such that the roller 93, when engaged by the arcuate cam 92, will rock the bell crank to operate the switch 97 to closed position. There is also another like roller bell-crank microswitch assembly immediately to the rear of the one just described (as viewed in Fig. 9), the arrangement being diagrammatically illustrated in Fig. 6 where I have designated as 98 the microswitch which is positioned oppositely of the dog 91 so as to be operated to closed position thereby.

A simple circuit arrangement for interconnecting the switches 97 and 98 with the two solenoids previously noted is also suggested in Fig. 6. Here a conductor 100 leading away from a source of current is in connection at 101 with one side of the solenoid 80 from whose opposite side a connection 102 leads to the switch 98 which is in connection with a second conductor 103 leading back to the current source. The switch 98 is adapted to be closed by the dog 91 for a relatively short period—long enough for the solenoid to retract the bolt 74 and permit the turntable to resume rotation for execution of its 90° cyclic movement in response to operation of the slip clutch 60. The conductor 100 also continues on for connection with one side of the solenoid 33 from whose opposite side a connection 105 leads to the switch 97, the circuit being completed by a connection 106 therefrom to the conductor 103. This latter switch when operated by the arcuate cam 92 is held closed for a relatively long period during which the lever stop 32 is rocked to a releasing position to permit the clutch 30 to transmit power to the screw shaft 40 to produce operation thereof. The positioning of the dog and cam on the timing disc 89 (see Fig. 9) is such that when energization of the solenoid 33 has ceased, there will be a relatively long time gap before the other solenoid 80 is energized to permit the turntable to advance through another 90°, and a relatively short time gap thereafter before the solenoid 33 is again energized to rotate the screw shaft 40 through another of its cyclic operations.

The helical flights 46 carried by the screw shaft 40 lie close at the lowermost point to the top side of each channelled arm 67 when positioned directly therebelow (see Fig. 4). By means presently to be described, a succession of hangers 111 are delivered to the outer end of each supporting arm 67 to depend therefrom for reception between the helical flights 46 to be advanced thereby in evenly spaced relation lengthwise of the arm. The flights thus serve as a feed screw for the hangers and act to separate them with a uniform spacing for the length of each supporting arm. When so strong upon the arm, a rack bar 110 may be slid endwise within the channel to underlie the hangers (see Fig. 3); when so

positioned the rack bar may be lifted from the channeled arm 67 and removed to a finishing station to carry the suspended hangers while still spaced evenly apart and ready for a painting or enameling treatment.

Welded or otherwise secured to the gear box 45 is a plate 115 which is extended alongside the feed screw to one side thereof (see Fig. 4) and preferably reinforced by a rib 116. This plate and rib constitute a bracket for support at its outer end of an arm 118 which extends transversely to provide a bearing 120 wherein is journaled a shank 121 which projects axially from the base end of a conical head 122 having outstanding screw threads 123. The shank 121 is 15 fitted into an axial socket at the outer end of the shaft 40 and pinned thereto so as to rotate therewith.

The forming machine which produces the hangers 111 (or other like articles) discharges them onto a magazine in the form of a downwardly inclined bar 125 from which the hangers are suspended and along which they slide by gravity to a desired delivery point. It is at this point (see Fig. 1) that I locate the conical head 122 which provides a controlled release for the hangers in their movement to the stirring machine of this invention. The projecting screw threads 123 are disposed close to the upper side of the magazine bar 125 so as to engage with the oncoming hangers 111 and, unless the conical head 122 be undergoing rotation, advance of the foremost hangers will be stopped, thereby causing succeeding hangers to stack up rearwardly thereof in the magazine. When rotation of the conical head is resumed, however, the hangers will be permitted to continue their gravity advance, but in spaced apart relation as determined by the spacing of the threads 123 which enter in between the oncoming hangers to control their release from the magazine.

The lower end of the magazine bar 125 lies just above the outer end of the proximate channeled arm 67 where underlapping inclined guides 127 upstand to receive each hanger 111 as it falls off the magazine and direct it onto the supporting arm 67 beneath the outermost convolutions of the helical flights 46. At this point each hanger 111 is successively engaged by the feed screw to be advanced along the supporting arm in a predetermined spaced relation to the remaining hangers thereupon. When substantially a full supply of hangers has been strung upon the supporting arm 67, operation of the feed screw is halted; the hangers 111 continuing to come off the forming machine then start accumulating on the magazine bar 125, and the channeled arm 67 swings out from under the feed screw in response to rotation of the turntable through 90°; a rack bar 110 is next slid into the channeled arm and then lifted therefrom to carry the strung hangers off the machine for operative positioning in a finishing station which may be but a step or two away.

Each cyclic movement of the turntable positions an empty channeled arm 67 operatively with respect to the feed screw. Concurrently with the completion of this movement, operation of the feed screw is resumed and also a controlled release of the hangers 111 a supply of which has been accumulating on the magazine bar 125. The capacity of (a) the conical head 122 to release the hangers for deposit on each supporting arm 67 and (b) of the feed screw to advance such hangers along the arm in spaced relation there-

upon is desirably such that, when allowance is made for the rest period of the feed screw, it will substantially equal the production capacity of the forming machine. By maintaining such a timing relationship, the hangers which accumulate on the magazine bar 125 during each rest period of the feed screw will be transferred onto the stringing machine during each cyclic operation of the feed screw, so that the magazine will 10 be substantially or completely exhausted when the feed screw is again halted concurrently with cyclic movement of the turntable to permit insertion of a rack bar and removal thereof with supported hangers to the finishing station.

At an earlier point in this description I have explained the operation of the electrical controls, viz. the two solenoids 33 and 80 which are energized at instants and for durations that are determined by the dog 91 and arcuate cam 92 on the constantly rotating timing disc 89. The two clutches controlled by these solenoids cause the turntable arms 67 and screw shaft 40 to operate at the moments and for the intervals above described to release hangers from the magazine and 20 advance them processional along each supporting arm 67 while the turntable remains at rest; when the bar is loaded, the feed screw stops to halt the advance of hangers and permit another supply thereof to accumulate in the magazine 25 125 concurrently with a 90° cyclic movement of the turntable to (a) shift the loaded supporting arm to a position for reception of a rack bar and its removal from the machine and (b) bring an empty supporting arm into loading position 30 35 whereupon operation of the feed screw is automatically resumed. It will be observed, therefore, that the stringing machine of this invention, while independent of the forming machine, is nevertheless desirably timed to operate in co- 40 ordinated relation therewith. By so doing, the output of the stringing machine is maintained at substantially the same capacity level as the machine which forms the hangers.

I claim:

- 45 1. A stringing machine having, in combination, a feed screw with helical flights mounted to rotate about a horizontal axis, a turntable disposed below the feed screw and mounted to rotate about a vertical axis, and a plurality of supporting arms 50 carried by the turntable and extended outwardly therefrom at equal distances apart and rotatable through a horizontal plane slightly below the helical flights of the feed screw to and from said feed screw, each arm providing a support where- 55 on hangers may be advanced from its outer end toward its inner end for stringing lengthwise thereof, the hangers when suspended from each supporting arm while in operative position relative to the feed screw being engageable by the 60 helical flights of the rotatable feed screw to be advanced along the arm in spaced apart relation, and a conical head having projecting screw threads, said head projecting from the outer end of the feed screw to rotate therewith and engage 65 a plurality of vertically disposed hangers sliding down an inclined magazine, the threads of the conical head entering in between the adjacent hangers to control their gravity descent preliminary to dropping onto the supporting arm near 70 its outer end for engagement by the helical flights of the feed screw.

- 75 2. A stringing machine according to claim 1 in which there is power means to operate the turntable and also the feed screw, one in timed relation with respect to the other.

3. A stringing machine according to claim 1 in which there is power transmission means from a common source to both the turntable and the feed screw, a clutch in each power transmission means, and control means in connection with each clutch to establish driving connections therethrough but at different periods of time.

4. For use with a hanger-forming machine including a magazine bar for accumulation of hangers and wherein the hangers are successively discharged from the magazine bar; an arm mounted horizontally for movement into and out of position in which it is adapted to extend longitudinally of and from the magazine bar, a stationary support extending horizontally longitudinally of said magazine bar in a plane above the plane in which said arm moves whereby said arm passes under the support in its path of travel relative to the magazine bar, a conveyor carried by said support and disposed over said arm longitudinally thereof in position for moving hangers along the arm and holding the said hangers spaced from each other, a member carried by said support and overlapping said magazine bar and constituting means for successively feeding hangers from the magazine bar onto the arm when the arm is opposite the magazine bar, said arm having longitudinally extending transversely spaced upstanding flanges upon upper edges of which the hangers rest, and an elongated bar-like member for removing hangers from the arms, the said bar-like member being of dimensions adapting it to be deposited upon the arm between the flanges thereof for approximately the full length of the arm and then moved upwardly and lift the hangers from the arm.

5. For use with a hanger-forming machine including a magazine bar free at one end and disposed at a downward incline toward its free end and along which hangers suspended from the bar are adapted to slide toward the free end of the magazine bar; an arm mounted horizontally for

movement into and out of a hanger-receiving position in which it extends longitudinally from the free lower end of the magazine bar, a stationary support extending horizontally in a plane above the plane in which said arm moves whereby the arm may pass under the support during its movement toward and away from the magazine bar, a conveyor carried by said support and disposed over said arm longitudinally thereof when the arm is in its hanger-receiving position and serving to move hangers along the arm in spaced relation to each other, and an auxiliary conveyor rotatably carried by said support and extending therefrom longitudinally of the first conveyor, the auxiliary conveyor being tapered toward its outer end and disposed in overlapping relation to the lower end portion of the magazine bar and having threads disposed close to the magazine bar and serving to successively move hangers off of the free end of the magazine bar onto said arm when in operation and also serving to hold hangers upon the magazine bar when not in motion.

6. The structure of claim 5 wherein the first conveyor is a rotatably mounted spiral conveyor and the auxiliary conveyor has a shank rotatably mounted through a portion of the support and coupled to the outer end of the spiral conveyor for turning with the spiral conveyor.

WALTER J. VAIL.
